NEW PHENYLOXY AND PHENYLALKOXY BENZOIC ACID AMIDES

Hans Suter and Hans Zutter, Schaffhausen, Switzerland, assignors to Eprova Limited, Schaffhausen, Switzerland
No Drawing. Filed June 3, 1960, Ser. No. 33,643
Claims priority, application Switzerland June 11, 1959
7 Claims. (Cl. 260—247.2)

The present invention relates to a group of new compounds consisting of phenoxy and phenylalkoxy benzoic acid aminoalkyl amides, which are suitable for and effective in the treatment of disturbances of the heart rhythm (heart arrhythmia).

The new compounds of this invention may be represented by the following general formula:

wherein n is an integer selected from zero to four, preferably 1 to 4, Am is a member selected from the group consisting of

and

in which R_1 is selected from the group consisting of hydrogen and a lower alkyl radical, alkylene is a lower alkylene radical containing at least 2 carbon atoms,

is a radical selected from the group consisting of piperidino, pyrrolidino and morpholino radicals and R_3 is selected from the group consisting of a lower alkyl and a lower hydroxy alkyl radical.

The invention also includes the acid addition salts of the above free bases with pharmacologically acceptable inorganic and organic acids, such as for example hydrochloric acid, sulphuric acid, lactic acid, citric acid or oxalic acid.

The preferred compounds of the invention are the dialkylaminoethyl amides of the 4-phenoxy and 4-phenylalkoxy benzoic acid.

The phenylalkoxy derivatives generally show a higher efficacy than the phenoxy derivatives, and they are consequently the compounds which are of particular value.

It has been found that the compounds with the structure defined above are excellently suitable for the treatment of heart arrhythmia as so-called "antiarrhythmics" or "anti-fibrillation agents." They are particularly characterised by an unusually high activity.

The anti-arrhythmic activities of the compounds according to the invention, as established in pharmacological test experiments and for example determined on the electrically stimulated isolated top of the right ventricle of the rat, showed activity values with rheobase, maximum frequency and excitation which are up to 100 times greater than those measured in concurrently conducted comparison experiments with procainamide (4-aminobenzoic acid-2'-diethyl-aminoethyl amide).

This extraordinary difference can be attributed to a different type of action mechanism.

2

4-aminobenzoic acid-2'-diethylamino-ethylamide is the therapeutic compound hitherto most widely used for the present indication.

4-phenylethoxybenzoic acid-2'-diethylaminoethylamide (see Example 3) is on average quite 100 times more active than procainamide.

4-benzylphenoxybenzoic acid - 2' - diethylaminoethylamide (Example 2) shows about half, and 4-phenoxybenzoic acid-2'-diethylaminoethylamide (Example 1) shows one third of the activity of the 4-phenylethoxy derivative (Example 3).

The acute toxicity of the compounds according to the invention is fairly low. It is only about twice as high as that of the very much less active 4-aminobenzoic acid-2'-diethylaminoethylamide.

As a result, a therapeutic index is produced for the compounds according to the invention which is several times higher by comparison with the therapeutic compound most used at the present time.

The compounds according to the invention are suitable both for oral administration, for example in the form of the free bases or their crystallized salts, and also for introduction into the organism by injection in the form of aqueous solutions of the acid addition salts.

The compounds according to the invention are most easily prepared by conversion of a reactive derivative of a phenoxy or phenylalkoxy benzoic acid, advantageously by conversion of a mixed acid anhydride thereof and an inorganic or organic acid, for example hydrochloric acid or a semi-ester carbonic acid, for example the ethyl carbonic acid, see *Helv. chim. Acta* 34 (1951), page 874, with a diamine of the formula

wherein Am has the meaning defined above, and recovering the amide thus formed.

As mixed acid anhydride, it is advantageous to use the corresponding acid chloride.

The reaction itself is preferably carried out in a solvent which is neutral with respect to acid chlorides, advantageously in a halogenated hydrocarbon (for example chloroform). The diamine is used in at least the equivalent quantity, but preferably in excess, this particularly simplifying the working up.

The temperature at which the reaction is carried out can vary within fairly wide limits, from less than 0° C. up to the boiling point of the solvent being used. The compounds according to the invention are generally isolated initially as a free base when using an excess of diamine, and as a "hydrochloride addition salt" when using exactly the equivalent quantity of diamine.

However salts with other acids which form addition salts with amines may be prepared by reaction of the free base, or the hydrohalide salts after conversion to the free base by treatment with a basic reagent such as sodium hydroxide or potassium carbonate, with the desired acid (e.g. sulphuric acid, nitric acid, lactic acid, tartaric acid, citric acid or oxalic acid, a pharmacologically acceptable acid being employed where the salt is to be the final compound). The above mentioned method is, however, not the only method which yields the desired compounds.

In addition to using any desired mixed acid anhydride as reactive derivative of a phenoxy and phenylalkoxy benzoic acid, it is also possible to use an ester thereof, for example a methyl or cyanomethyl ester (see for example *Helv. Chimica Acta* 38 (1955) pages 69, 80, 83, 1508; 39 (1956) page 872). The actual reaction conditions must of course be adapted to the particular case.

It is also in certain circumstances possible for the phenoxy and phenylalkoxy benzoic acids to be directly reacted to form the amides.

Finally, the reaction with the amine of the general formula

wherein H—Am is a diamine of the formula

in which formula B is a member selected from the group consisting of

can also be carried out in stages, by

(1) a reactive derivative of a phenoxy and phenylalkoxy benzoic acid being first of all reacted with NH_3 to an amide of the general formula

and this thereafter being converted by reaction with a reactive ester of an aminoalcohol of the general formula

into a compound of the Formula I, or by

(2) a reactive derivative of a phenoxy or phenylalkoxy benzoic acid being first of all transformed by reaction with a reactive ester of an alcohol of the general formula

reaction with a free aminoalcohol of the formula $\text{H}_2\text{N—alkylene—OH}$ and subsequent esterification into a reactive ester of a hydroxy alkyl amide of the general formula

and thereafter this reactive ester is converted by further reaction with an amine of the general formula

into a compound of the general Formula I.

The invention is further illustrated by the following examples:

EXAMPLE 1

4-Phenoxy-Benzoic Acid-2'-Diethylaminoethylamide

25.7 parts by weight of 4-phenoxy benzoic acid and 60 parts by volume of thionyl chloride are boiled under reflux for 6 hours. The excess thionyl chloride is distilled off in vacuo. The resultant residue is taken up in a little alcohol-free chloroform and again evaporated. This operation is repeated once more.

In this way, there are obtained 28 parts by weight (i.e. about 100% of the theoretical) of 4-phenoxybenzoyl chloride.

This acid chloride is dissolved in 60 parts by volume of chloroform and added dropwise over a period of 1 hour and while stirring to a solution of 29 parts by weight of 2-diethylaminoethylamine in 150 parts by volume of chloroform. The reaction solution is then concentrated by evaporation in vacuo.

The evaporation residue is taken up in diethylether and a large quantity of water and shaken. The ethereal solution is separated out and repeatedly washed with water. After evaporating the dried ether solution, there remain 35 parts by weight of a thickly liquid oil, consisting of 4-phenoxybenzoic acid-2'-diethylaminoethylamide, which is scarcely soluble in water, but is readily soluble in dilute aqueous mineral acids and organic solvents.

Micro-analysis, calculated for $\text{C}_{19}\text{H}_{24}\text{O}_2\text{N}_2$ (molecular weight 312.40)

C calculated 73.04%; found 73.09%.

H calculated 7.74%; found 7.57%.

N calculated 8.97%; found 8.73%.

The hydrochloride of this aminoalkylamide is obtained by dissolving the base in dry ether and adding one equivalent of ethereal hydrogen chloride. The hydrogen chloride initially precipitates in the form of an oil. The ether is decanted and the oily salt is triturated with ethyl acetate, whereupon it crystallizes. After recrystallization from ethyl acetate with addition of some i-propanol or from benzene, the hydrochloride melts at 114 to 116° C. It is readily soluble in water, alcohols and chloroform, but is less soluble in cold ethyl acetate, benzene and petroleum ether.

EXAMPLE 2

4-Benzylbenzoic Acid-2'-Diethylaminoethylamide

15 25 parts by weight of 4-benzylbenzoic acid and 100 parts by weight of thionyl chloride are gently boiled for about 4 hours under reflux. The excess thionyl chloride is evaporated. The evaporation residue is taken up in chloroform and the solution again concentrated by evaporation. The 4-benzylbenzoyl chloride thus obtained is dissolved in 70 parts by volume of chloroform, and added dropwise over a period of approximately 1 hour and while stirring to a solution of 30 parts by weight of 2-diethylaminoethylamine in 150 parts by volume of chloroform. The reaction solution is concentrated by evaporation, the residue is taken up in ether and water, the ether solution is separated, washed with water and evaporated. The evaporation residue crystallizes after a short time. It can be recrystallized from a large quantity of petroleum ether (B.P. 60 to 90° C.) or from a small quantity of i-propylether or from a mixture of both.

20 The 4-benzylbenzoic acid-2'-diethylaminoethylamide obtained in this manner melts at 64 to 65° C. It is readily soluble in most organic solvents and in aqueous dilute mineral acids, but is scarcely soluble in water.

25 Microanalysis, calculated for $\text{C}_{20}\text{H}_{26}\text{O}_2\text{N}_2$ (molecular weight 326.42)

C calculated 73.59%; found 73.89%.

H calculated 8.03%; found 8.00%.

30 N calculated 8.58%; found 8.57%.

EXAMPLE 3

4-Phenylethoxy Benzoic Acid-2'-Diethylaminoethylamide

45 18.1 parts by weight of 4-phenylethoxybenzoic acid and 40 parts by volume of thionyl chloride are boiled under reflux for 6 hours. The solution is then concentrated by evaporation and the residue is treated with chloroform as described in Example 1. The 4-phenylethoxybenzyl chloride thus obtained is dissolved in 60 parts by volume of alcohol-free chloroform and added dropwise in about 50 1 hour to a solution of 18.6 parts by weight of 2'-diethylaminoethylamine in 150 parts by volume of chloroform.

55 After another hour, the reaction solution is concentrated by evaporation and the residue is taken up in diethyl ether and a large quantity of water and shaken. The ethereal solution is separated, repeatedly washed in water, dried and evaporated.

60 The residue (23.4 parts by weight, i.e. 92% of the theoretical), consisting of 4-phenylethoxybenzoic acid-2'-diethylaminoethylamide, crystallizes on being triturated with petroleum ether. It can be recrystallized from petroleum ether (B.P. 60 to 90° C.).

Melting point: 65 to 66° C.

65 Microanalysis, calculated for $\text{C}_{21}\text{H}_{28}\text{O}_2\text{N}_2$ (molecular weight 340.45)

C calculated 74.08%; found 74.29%.

H calculated 8.29%; found 8.19%.

N calculated 8.23%; found 8.26%.

70 4-phenylethoxy benzoic acid-2'-(diethylamino)ethylamide is sparingly soluble in water.

A form of the compound which is suitable for use as an injection solution is obtained by converting the free base into one of its pharmacologically acceptable water-

soluble salts, in which case the procedure is for example as follows:

(a) 5.0 g. of the free base (molecular weight 340.45) are dissolved in 14.7 cc. of extremely pure normal hydrochloric acid solution (the exactly equivalent quantity), brought to the desired concentration by adding extremely pure twice distilled water, filtered until sterile after control of the pH value, placed in ampoules and if necessary sterilized again.

(b) 5.0 g. of the free base are mixed with 14.7 ccm. of a pure normal aqueous lactic acid solution and the solution which is obtained is further treated as in the above Example (a).

EXAMPLE 4

4-Phenylethoxy Benzoic Acid-3'-Dimethylamino-n-Propyl Amide

Replacement of 2-diethylaminoethylamine in Example 3 by 16.3 parts by weight of 3'-dimethylamino-n-propylamine provides in exactly the same way 4-phenylethoxybenzoic acid-3'-dimethylamino-n-propylamide, which is recrystallized from petroleum ether. (B.P. 60 to 90° C.)

Melting point 70 to 72° C.

Microanalysis, calculated for $C_{20}H_{26}O_2N_2$ (molecular weight 326.43)

C calculated 73.59%; found 73.30%.

H calculated 8.03%; found 7.84%.

N calculated 8.58%; found 8.37%.

4-phenylethoxy-benzoic acid - 3' - dimethylamino - propylamide is scarcely soluble in water but is more readily soluble in dilute mineral acids, dilute aqueous lactic acid, citric acid, tartaric acid and oxalic acid and is very readily soluble in most organic solvents with the exception of cold petroleum ether, diisopropyl ether and cold benzine.

EXAMPLE 5

4-Phenylethoxybenzoic Acid-2'-N(piperidino)-Ethylamide

The replacement of 2-diethylaminoethylamine of Example 3 by 20.5 parts by weight of N(2-aminoethyl)-piperidine provides in analogous manner the 4-phenylethoxy-benzoic acid-2'-N(piperidino)-ethylamide, which immediately crystallizes in the impure form. It can be successfully recrystallized from a relatively large volume of petroleum ether (B.P. 60 to 90° C.) or from i-propanol diluted with a little water.

Melting point 111 to 112° C.

Microanalysis calculated for $C_{22}H_{28}O_2N_2$ (molecular weight 352.46)

C calculated 74.96%; found 75.08%.

H calculated 8.01%; found 7.97%.

N calculated 7.95%; found 7.86%.

4-phenylethoxy-benzoic acid - 2' - N(piperidino) - ethylamide is scarcely soluble in water and cold petroleum ether, more readily soluble in aqueous mineral acids, aqueous lactic acid, citric acid, tartaric acid and oxalic acid and very readily soluble in ethanol, acetone and ethyl acetate.

EXAMPLE 6

4-Phenylethoxy-Benzoic Acid-2'-N-(Morpholino)-Ethyl N'-Methylamide

6.4 parts by weight of 4-phenylethoxy benzoic acid chloride are dissolved in about 20 parts by volume of chloroform and added dropwise in about 1 hour to a solution of 7.4 parts by weight of N(N'-methylaminoethyl)morpholine in 35 parts by volume of chloroform. The reaction solution is then concentrated by evaporation. The residue is taken up in ether and water. The ethereal solution is separated out, washed with water and evaporated. The residue (8.1 parts by weight, i.e. 88% of the theoretical) crystallizes on standing and can be recrystallized from di-i-propylether or a few ethyl acetate. The obtained 4-phenylethoxy-benzoic acid-2' - N - (morpholino)-

ethyl-N'-methylamide melts at 107 to 108° C. It is readily soluble in lower alcohols, chloroform, ethyl acetate and dilute mineral acids, but scarcely soluble in water and benzines.

5 Equivalent weight: calculated for $C_{22}H_{26}O_3N_2$ calculated: 368.46; found 370.

The hydrochloride of this compound melts after recrystallization from i-propanol at 184 to 185° C. It is readily soluble in water, chloroform and in lower alcohols, but is less soluble in benzene.

Microanalysis calculated for $C_{22}H_{26}O_3N_2Cl$ (molecular weight 404.93)

Cl calculated 8.76%; found 8.76%.

EXAMPLE 7

4-Phenylethoxy-Benzoic Acid-2'-N-(Pyrrolidino)-Ethylamide

Replacement of N(N'-methylaminoethyl)-morpholine in Example 6 by about 6 parts by weight of N(2-aminoethyl)-pyrrolidine provides in analogous manner the 4-phenyl-ethoxy-benzoic acid-2'-N(pyrrolidino)-ethyl amide. It is scarcely soluble in water but readily soluble in dilute mineral acids and lower alcohols.

EXAMPLE 8

N(4-Phenylethoxy-Benzoyl)-N'-Methylpiperazine

5 parts by weight of 4-phenylethoxy-benzoyl chloride are dissolved in about 10 parts by volume of chloroform and added dropwise while stirring to a solution of 4.5 parts by weight of N-methyl-piperazine in 20 parts by volume of $CHCl_3$. The reaction solution is evaporated to dryness. The residue is taken up in water and diethyl ether and shaken. The ethereal solution is separated out, washed with water, dried and evaporated. The resultant residue —N(4 - phenylethoxy-benzoyl)-N'-methyl-piperazine — (7.3 parts by weight) is a viscous oil, which is scarcely soluble in water but readily soluble in aqueous dilute mineral acids and in most organic solvents.

The hydrochloride melts after recrystallization from a mixture of ethyl acetate and i-propanol at 204° C.

Microanalysis, calculated for $C_{20}H_{29}O_2N_2Cl$ (molecular weight 360.88)

45 C calculated 66.56%; found 66.79%.

H calculated 6.94%; found 7.08%.

N calculated 7.77%; found 7.82%.

Cl calculated 9.83%; found 9.60%.

50 The hydrochloride is readily soluble in water, chloroform, methanol, ethanol and hot i-propanol, but sparingly soluble in cold ethyl acetate and benzene.

EXAMPLE 9

N(4-Phenylethoxy-Benzoyl)-N'-(2'-Hydroxyethyl)-Piperazine

5 parts by weight of 4-phenylethoxy-benzoyl chloride in 10 parts by volume of chloroform are added dropwise while stirring to 6 parts by weight of N-(2'-hydroxyethyl)-piperazine in 20 parts by volume of chloroform. The reaction mixture is diluted with chloroform and repeatedly washed with water, dried and evaporated. The viscous oily residue (6.3 parts by weight) — free N(4-phenylethoxy-benzoyl - N' - 2' - (hydroxyethyl)-piperazine — is sparingly soluble in water and diethyl ether. It is dissolved in ethyl acetate and converted by addition of etheric hydrochloric acid to the hydrochloride, which melts after twice recrystallization from i-propanol at 183° C.

70 Microanalysis, calculated for $C_{21}H_{27}O_3N_2Cl$ (molecular weight 390.94)

N calculated 7.16%; found 7.00%.

Cl calculated 9.06%; found 9.13%.

75 The hydrochloride is readily soluble in water, acetic

acid, hot ethanol and i-propanol and soluble in chloroform, but scarcely soluble in other solvents.

As stated above, the herewith described, new aminoalkylamine compounds have proved to be effective agents, which are useful in the treatment of disturbances of the heart rhythms. They are very well tolerated and do not show undesired secondary effects. In pharmacological experiments in vitro and the dog, an excellent antiarrhythmic activity of the new compounds was disclosed against experimental induced pathogenic arrhythmias. For oral application the compounds can be given in capsules of 0.5 g. and for intravenous use they can be applied as salt solutions in ampoules. The preferred daily dose is between 0.3 g. and 3.0 g. (in most cases 0.5 to 2 g.).

The antiarrhythmic activity in men and the therapeutic effect with regard to its safe, effective and reliable usefulness were verified in clinical tests, for instance with 4-phenylethoxybenzoic acid - 2' - diethylaminoethylamide (see Example 3). In most cases a prompt and continual disappearance of the pathological arrhythmic phenomena could be obtained.

What we claim is:

1. A chemical compound selected from the group con-

sisting of 4-phenyloxy and 4-phenylalkoxy benzoic acid amino alkyl amide of the formula

wherein n is an integer selected from zero to four, Am is a member selected from the group consisting of

and

in which R_1 is selected from the group consisting of hydrogen and the lower alkyl radical, alkylene is the lower alkylene radical of at least 2 carbon atoms,

is the radical selected from the group consisting of piperidino, pyrrolidino and morpholino radicals, and R_3 is selected from the group consisting of the lower alkyl and lower hydroxyalkyl radical, and acid addition salts of said amino alkyl amide with pharmacologically acceptable inorganic and organic acids.

2. The 4-benzyloxybenzoic acid-2'-diethylaminoethylamide of the formula

3. The 4-phenylethoxybenzoic acid-2'-diethylaminoethylamide of the formula

4. The 4-phenylethoxybenzoic acid-3'-diethylaminoethylamide of the formula

5. The 4-phenylethoxybenzoic acid-2'-N(piperidino)-ethylamide of the formula

6. The 4-phenylethoxybenzoic acid-2'-N-(morpholino)-ethyl-N'-methylamide of the formula

7. The N(4-phenylethoxybenzoyl)-N'-methyl-piperazine of the formula
